ABSTRACT OF THE DISCLOSURE

The runner of a hydraulic machine of the Francis type is surrounded by an annular blade array mounted for free wheeling rotation about the main runner when operating as a turbine, and securable to the runner to increase the effective runner diameter when the machine operates as a pump.

The present invention relates to rotary hydraulic machines and more particularly to pump-turbines in which the runner-impeller is so constructed that it is of relatively small diameter when acting as a turbine and is relatively larger in diameter when acting as a pump.

It has long been desired to utilize a rotary fluid machine either as a pump or as a turbine, selectively, and at different times. Such a machine is called a pump-turbine. When operated as a pump, it is driven by an electric motor and when operated as a turbine, it drives the electric motor which then functions as a generator.

One of the problems associated with a pump-turbine is that when the machine operates as a pump, the linear peripheral speed of the impeller must be higher than the linear peripheral speed at which it operates as a turbine for reasonable efficiency. However, under both operating conditions the rotational speed must remain constant, for use with a single speed motor-generator.

The prior art has recognized this particular problem and has provided several proposed solutions. One such proposed solution was to provide both a motor and a generator having means to alternately connect them to the pump-turbine, the motor being designed to operate at a different constant speed from that of the generator. This solution has the disadvantage of being overly expensive, since it required two electrical machines and had a further disadvantage of requiring complex coupling devices.

Another proposed solution was to provide a specially constructed motor-generator capable of operation at two speeds. However, this solution has proven undesirably expensive due to the necessary added cost for the special motor-generator.

Another problem associated with such rotary fluid machinery is the inability to operate a turbine over wide variations of hydraulic heads. Prior art systems were proposed which provided two interchangeable runners or impellers which were intended to be used depending on the differing hydraulic heads. This proposal is not satisfactory since it requires the manufacture of an additional runner or impeller and also requires that the unit be shut down for a considerable length of time while the runner or impeller is changed; this is uneconomic. Furthermore these systems are only partially successful and cannot be utilized in a pump-turbine installation as they are restricted to either pumps or turbines.

The principal object of the present invention is to provide an improved pump-turbine wherein the motor-generator operates at a constant speed and wherein the higher constant speed for pumping is obtained by increasing the overall diameter of the runner-impeller, thus effecting a higher linear speed at its periphery.

Another object of the present invention is to provide

2

a pump-turbine which does not embody difficult engineering and constructional problems and is of relatively low cost.

A further object of the present invention is the provision of a pump-turbine capable of efficient use within a wide range of hydraulic heads.

A still further object of the invention is the provision of a pump-turbine which may be readily and easily changed from one mode of operation to the other.

10 A still further object of the present invention is to provide a pump-turbine which requires only a very short downtime for changing its mode of operation.

The present invention provides a runner-impeller in which the outer portion is of larger diameter and is constructed as a separate piece, said separate piece being annular and comprising blade portions and portions of the shrouds. This separate annular portion is called a "free-wheel."

When the machine operates as a pump, the rotation 20 is in one direction and the free-wheel is attached to and is driven by the main runner-impeller.

However, when the machine operates as a turbine, the rotation is in the opposite direction and the main runner-impeller is disengaged and "runs away" from the free-wheel. The free-wheel portion automatically assumes a speed lower than the synchronous speed of the machine, that is, the speed where it presents the least interference to the water coming from the distributor to the main runner-impeller. The blade area of the main runner-impeller is adequate to develop the power of the water, and the radius of the leading edge of its blades is chosen for optimum efficiency and power as a turbine, with due allowance being made for the unavoidable interference of the free-wheel.

35 The construction and operation of a rotary hydraulic machine in accordance with the present invention will be further understood, together with further objects and advantages thereof from the following specifications and drawings wherein:

40 FIG. 1 is a fragmentary radial vertical section of a rotary hydraulic machine incorporating the preferred execution of the invention.

FIG. 2 is a fragmentary radial vertical section of a rotary hydraulic machine incorporating an alternative 45 execution of the invention.

Referring now to the drawings wherein like or corresponding parts have like or corresponding reference numerals and with particular reference to FIG. 1, when the machine operates as a turbine, water under pressure 50 passes from the inlet casing 10 to a distributor 11, flows through the free-wheel assembly shown generally at 12 and thence to the main runner-impeller shown generally at 13; the water is then discharged at a reduced pressure into draft tube 14. Main runner-impeller 13 comprises 55 blades 15 which are connected together by a crown or upper shroud 16 and a lower or band shroud 17; shaft 18 is rigidly secured to crown shroud 16. The end of shaft 18 remote from crown shroud 16 is coupled to a motor-generator (not shown).

60 When the machine operates as a pump, shaft 18 is rotated by the motor-generator which rotates the main runner-impeller assembly 13. For this mode of operation the free-wheel assembly 12 is rigidly attached to assembly 13, the direction of rotation is then reversed and the 65 flow of water is from draft tube 14 to casing 10.

The rotating assembly comprising free-wheel 12, runner-impeller 13 and shaft 18 are enclosed within upper stationary structure 19 and lower stationary structure 20.

70 To locate and support free-wheel 12 when it is disconnected from main runner-impeller assembly 13, an annular bearing pad 21 is provided, said bearing pad

being attached to the lower stationary structure 20 by means of a series of bolts 22, only one of which is shown.

The free-wheel assembly 12 comprises an upper shroud 23, a lower shroud 24, said shrouds being separated from each other by a series of contoured blades 25 similar in number to blades 15 of the main runner-impeller 13.

The crown shroud 16 of runner-impeller 13 has an extension 26 which substantially overlaps upper shroud 23 of free-wheel 12, and the free edge 27 of band shroud 17 is substantially in line with the lower shroud 24 of free-wheel 12.

The upper shroud 23 of free-wheel 12 is provided with a series of countersunk holes 28 and extension 26 has a similar matching number of threaded holes 29. When it is desired to operate the machine as a pump, free-wheel 12 and runner-impeller 13 are unitized by means of a series of fasteners such as bolts, said bolts passing through countersunk holes 28 then into threaded holes 29. When it is desired to operate the unit as a turbine, these bolts are removed and the free-wheel assembly 12 is thereby freed from the runner-impeller 13.

It will be seen by referring to the foregoing description that as a turbine designed for variable heads, the unit will function as follows: Under high head, the velocity and direction of water flow from the distributor is such that it imparts torque in the proper direction to the free-wheel assembly 12, rotating said free-wheel at the synchronous speed of the machine. This water in turn imparts torque to the main runner-impeller 13 and hence to the generator (not shown).

At low heads the velocity and direction of the water flow is such that if the free-wheel assembly 13 is rotated at the synchronous speed it would receive torque in the wrong direction therefore it is left free to rotate at a lower speed and thus rotates torque free between the distributor 11 and the main runner-impeller 13.

Referring now to FIG. 2 which shows an alternative embodiment of the invention, band shroud 17 is extended to form a lip shaped protrusion 30 on which a bearing 31 is formed. Bearing 31 locates and supports the lower shroud 24 of free-wheel 12. The upper shroud 23 of free-wheel assembly 12 is located by an upper bearing 32 which in turn is attached to a stationary extension 33, said extension 33 being rigidly attached to the upper stationary structure 19.

Splines 34 are formed on the inner edge of upper shroud 23 of free-wheel unit 12 and splines 35 are provided on the outer edge of the runner-impeller crown shroud 16, splines 34 and 35 being in face to face relationship. A key 36 or a series thereof is provided to lock together components 12 and 13 when it is desired to run the unit as a pump. It will be understood that key 36 may be inserted into and disengaged from splines 34 and 35 by any suitable means, either manually or by any mechanical aid.

It will be seen that I have provided an improved pump-turbine of low cost which presents no difficult engineering or constructional problems. It is capable of efficient use within a wide range of heads, and in both embodiments the unit may be readily changed from one mode

of operation to the other. Further, the pump-turbine of the present invention requires only a short shut down period for conversion from one mode of operation to the other.

It will be obvious to those skilled in the art that various changes may be made without departing from the spirit of the invention and therefore the invention is not limited to what is shown in the drawings and described in the specification but only as indicated in the appended claims.

10. What is claimed is:

1. In a fluid machine, a shaft, a pair of inner spaced shrouds having blades between them connected to said shaft for rotation therewith, a free-wheel unit outwardly of said inner shrouds and blades and comprising a pair 15 of outer spaced shrouds respectively and generally in line with the free edges of said inner shrouds, said free-wheel unit further comprising blades between said outer shrouds, bearing means journaling said free-wheel unit, a said inner shroud having splines at its outer edge, a said outer shroud having splines at its inner edge in juxtaposition with said first-mentioned splines, and movable key means selectively engageable with said splines.

2. The fluid machine of claim 1, and motor means for moving said key means.

25. 3. The fluid machine of claim 1, said other of said inner shrouds at the outer periphery thereof supporting said bearing means.

4. In a rotary turbo machine having a shaft, a main runner connected thereto having at least one shroud 30 member, a plurality of blades attached to said shroud member arranged relative to a portion of the machine casing for passage of working liquid therethrough in energy transfer relation with the runner, the improvement comprising a free wheel unit having an array of blades arranged 35 in the form of an annulus interposed in the liquid passage radially outwardly of said runner between the casing and the runner and axially aligned therewith for interaction with the working liquid on passage through the runner, said free wheel blades being supported by a hubless-annular shroud member, bearing means supporting said shroud member for rotation independently of said main runner, and interlocking means between the peripheral edges of said shroud members for selective 40 connection and disconnection of said free wheel unit with said runner when operating as a pump and a turbine 45 respectively.
